RONALD LISTER, OF CHORLTON-CUM-HARDY, ENGLAND, ASSIGNOR TO WESTINGHOUSE ELECTRIC & MANUFACTURING COMPANY, A CORPORATION OF PENNSYLVANIA.

KNIFE-BLADE SWITCH.

1,264,404.

Specification of Letters Patent. Patented Apr. 30, 1918.

Application filed June 27, 1917. Serial No. 177,185.

To all whom it may concern:

Be it known that I, RONALD LISTER, a subject of the King of Great Britain, and a resident of Sandy Lane, Chorlton-cum-Hardy, in the county of Lancaster, England, have invented a new and useful Improvement in Knife-Blade Switches, of which the following is a specification.

My invention relates to electric switches and particularly to knife-blade switches.

The object of my invention is to provide a knife-blade switch that shall have its hinge and contact-jaw members formed entirely of strip metal.

According to my invention, the hinge and contact-jaw members of a knife-blade switch are formed of metal strips of substantially L-shape that are spaced apart and secured to, and supported by, one or more metal strips of L-shape to constitute a terminal member.

In order that the nature of my invention may be clearly understood, it will now be described with reference to the accompanying drawings, in which Figure 1 is a front elevational view of a switch embodying my invention; Fig. 2 is a side elevational view of a single-blade switch having hinge and contact-jaw members constructed in accordance with my invention; Fig. 3 is a detail plan view of the hinge-jaw members shown in Figs. 1 and 2; Fig. 4 is a detail side elevational view of a modified form of hinge-jaw member embodying my invention; Fig. 5 is a detail side elevational view, and Fig. 6 is a detail plan view illustrating modified forms of jaw members embodying my invention.

In Figs. 1 to 3, inclusive, a switch blade 1 is pivoted to a hinge-jaw member 2 by a bolt 3 and is adapted to engage a contact-jaw member 4 when the switch is closed. As the hinge and contact-jaw members are both constructed in a similar manner, the hinge-jaw member only will be described. The jaw members are constructed of two pieces of metal strip 5 and 6 that are bent to an L-shape, substantially as shown in Fig. 3 of the drawings, and arranged with one parallel face 7 of the strip 5 substantially parallel to one face 8 of the strip 6. The strips are spaced a suitable distance apart to receive the switch blade 1 and the other faces

9 and 10 of the strips that are perpendicular to the parallel faces 7 and 8 are located in substantially the same plane.

Another pair of strips 11 and 12 of substantially L-shape are arranged similarly to the contact strips above described, but their parallel faces are closer and preferably in contact with each other, as shown at 13 in Fig. 2. The two perpendicular faces 14 and 15 are located opposite to and touching the faces 9 and 10 of the contact strips 5 and 6. In the drawings, the parallel faces 7 and 8 of the contact strips 5 and 6 are arranged with their planes perpendicular to the parallel faces of the strips 11 and 12 that are in contact along the line 13, but the two pairs of strips may be arranged otherwise and with the planes of their parallel faces parallel if so desired. The four strips are so secured together by means of bolts 16 which pass through the switch base or panel 17 as to hold the jaw member firmly in position thereon. The parallel portions of the strips 11 and 12 project through the base or panel parallel with the bolts 16 forming a terminal to which the switch leads may be directly secured. The planes of the terminal parts of the strips are horizontal in the arrangement shown in the drawings but it is clear that the strips 11 and 12 may be rotated through a right angle around a horizontal axis in order that the planes of their terminal parts may be vertical without interfering with the manner in which the contact strips are secured to the supporting strips.

To improve the appearance of the switch, the portions of the L-shaped pieces that are applied to the base or panel may be covered by a metal cap, as shown at 18, said cap, which is preferably pressed to shape, being located under the heads of the bolts 16.

In Fig. 4 of the drawings, two strips 5 and 6 of substantially L-shape that form a switch jaw member are supported by a single L-shaped strip to one limb 19 of which the jaw member is secured, while the other limb 20 projects through the switch base or panel. The limb 20 may obviously be arranged in a plane perpendicular to the plane of the contact faces of the jaw members 5 and 6, as shown, or it may be in a plane parallel to said plane. In this modi-

ification, each of the contact strips may be secured to the base and to the strip by a single bolt, as shown.

In Figs. 5 and 6 of the drawings, a pair of hinge-jaw members for a knife-blade switch having two blades is illustrated. The contact strips 21, 22, 23 and 24 are nested in such a manner as to permit of a single bolt 25 passing through a suitable number 10 of strips in order to secure them to the base (not shown). The supporting strips 26, 27, 28 and 29, as shown in Fig. 5 of the drawings, are equal in number to the contact strips, being of substantially L-shape 15 and nested in a similar manner. The two pairs of supporting strips 26 and 27 may be spaced apart from the strips 28 and 29, if desired, or the dimensions may be such that their parallel faces shall be touching. 20 Obviously, the number of L-shaped supporting strips may be different from the number of the contact strips or the latter may be secured to a single L-shaped strip in the manner hereinbefore described with reference to Fig. 4 of the drawings. 25

My invention is not limited to the particular construction illustrated, but may be variously modified without departing from the spirit and scope of the invention as set forth in the appended claims.

I claim as my invention:

1. A knife-blade switch comprising members of substantially L-shape spaced apart to constitute jaw members and other members of L-shape secured thereto to constitute a terminal member.

2. A knife-blade switch comprising conducting members of L-shape the longer legs of which are spaced apart to constitute a 40 jaw member and a similar conducting member of L-shape having its shorter leg operatively connected to the shorter legs of the other conducting members to constitute a terminal member.

3. A knife-blade switch comprising a plurality of members of L-shape some of which are spaced apart to constitute jaw members and others of which are secured thereto to constitute a terminal member.

4. A knife-blade switch comprising a plurality of conducting members of L-shape having arms of different lengths, some of said members having their relatively long arms spaced apart to constitute jaw mem-

bers and others of said members having 55 their relatively short arms connected to the relatively short arms of the jaw members to constitute terminal members.

5. A switch member comprising a plurality of conducting members of L-shape 60 spaced apart to constitute a jaw member and a conducting member of L-shape secured to the other members of L-shape to constitute a terminal member.

6. A switch member comprising a plurality of conducting members of L-shape 65 spaced apart to constitute a jaw member and a conducting member of L-shape having one of its legs secured to one leg of each of the other members of L-shape to constitute a 70 terminal member.

7. A switch member comprising a plurality of conducting members of L-shape 75 spaced apart to constitute a jaw member, a conducting member of L-shape having one of its legs secured to one leg of each of the other members of L-shape to constitute a terminal member and a cap member for the legs that are secured together.

8. A switch member comprising a plurality of conducting members of L-shape 80 having certain of the arms thereof separated to constitute a jaw member and one or more similar members secured to the other arms of the jaw member to constitute a terminal 85 member.

9. A switch member comprising a plurality of conducting members of L-shape 90 spaced apart to constitute a jaw member and a conducting member having two portions at substantially right angles with respect to each other, one of said portions being secured to the members of L-shape to constitute a terminal member.

10. A switch member comprising a plurality of conducting members having arms of different lengths, some of said members having their relatively long arms spaced apart to constitute jaw members and others of said members having their relatively 100 short arms connected to the relatively short arms of the jaw members to constitute terminal members.

In testimony whereof, I have hereunto subscribed my name this 25th day of May, 1917.

RONALD LISTER.
